UNITED STATES PATENT OFFICE.

JOHN M. McCABE, OF FAIRMOUNT, ILLINOIS.

DESIGN FOR A ROOFING-TILE.

SPECIFICATION forming part of Design No. 24,491, dated July 16, 1895.

Application filed April 20, 1895. Serial No. 546,566. Term of patent 14 years.

To all whom it may concern:

Be it known that I, JOHN M. McCABE, a citizen of the United States, residing at Fairmount, in the county of Vermilion and State of Illinois, have invented a new and original Design for Roofing-Tiles, of which the following is a specification.

This invention relates to a new and original design for roofing-tiles; and it has for its object to provide a design of this character that shall be both useful and ornamental.

The leading feature of the design resides in a rectangularly-shaped tile-body, the obverse side of which is provided with a large rectangularly-shaped depression bounded at one end and at its opposite sides with beveled faces; a tapered projection located between the opposite sides of the large rectangular-shaped depression and entirely surrounded by beveled faces sloping to the floor of the large depression; a pair of spaced parallel ribs extending transversely across the upper end of the tile-body and having beveled side faces; small rectangular-shaped depressions located between one end of the large depression and the innermost of said ribs, said small rectangularly-shaped depressions being bounded at transversely-opposite sides with beveled faces, and V-shaped valleys disposed longitudinally of the tile-body between the large and small rectangular depressions, and the reverse side of which tile-body is provided, near the opposite side edges thereof, with semicircular grooves extending longitudinally of the tile-body, and one of which grooves is larger than the other; a pair of spaced parallel ribs extending transversely across the lower end of the tile-body and having beveled side faces; a single rib extending transversely across the upper end of the tile-body and having an inner beveled side face; a semicircular depression arranged between the parallel ribs at the lower end of the tile-body; a semiconical-shaped depression disposed longitudinally of the tile-body in alignment with the depression between the pair of ribs; a pair of inclined ribs disposed longitudinally of the tile-body and respectively located at opposite sides of the semiconically-shaped depression, said longitudinally-disposed ribs being pro-

vided with beveled side faces; a V-shaped depression disposed transversely of the tile-body, adjacent to one end of the longitudinally-disposed ribs, and a small rectangular-shaped depression arranged between the V-shaped depression and the single rib at one end of the tile-body and bounded at all four of its sides by beveled faces.

In the drawings, Figure 1 is a perspective view of the obverse side of a tile-body embodying the design. Fig. 2 is a similar view of the reverse side of the tile-body. Fig. 3 is a longitudinal sectional view of the tile-body.

Referring particularly to the drawings, the numeral 1 designates the tile-body, which is of a rectangular shape. The rectangularly-shaped body 1 is provided on its obverse side with a large rectangularly-shaped depression 2, that is bounded at one end and at its opposite sides with beveled faces 3. The obverse side of the rectangular body is also provided with a tapered projection 4, located between the opposite sides of the depression 2 and entirely surrounded by beveled faces 5, sloping to the floor of said depression 2; a pair of spaced parallel ribs 6, extending transversely across the upper end of the body 1 and having beveled side faces 7; small rectangularly-shaped depressions 8, located between one end of the depression 2 and the innermost of said ribs 6, said small rectangularly-shaped depressions 8 being bounded at transversely-opposite sides by beveled faces 9, and V-shaped valleys 10, disposed longitudinally of the tile-body between the large and small depressions 2 and 8. The reverse side of the rectangular body 1 is provided near the opposite side edges thereof with semicircular grooves 11, extending longitudinally of the body, and one of which grooves is larger than the other; a pair of spaced parallel ribs 12, extending transversely across the lower end of the body and having beveled side faces 13, the lowermost of said ribs 12 having a pair of lug-like projections 14; a single rib 15, extending transversely across the upper end of the body 1 and having an inner beveled side face 16; a semicircular depression 17, arranged between the parallel ribs at the lower end of the tile-body 1; a semiconical-shaped depression 18, dis-

(aure)

posed longitudinally of the tile-body in alignment with the depression between the pair of ribs; a pair of inclined ribs 19, disposed longitudinally of the body 11 and respectively located at opposite sides of the semiconically-shaped depression 18, said ribs 19 being provided with beveled side faces 20; a V-shaped depression 21, disposed transversely of the tile-body, adjacent to one end of the ribs 19, said depression 21 having therein, near its ends, step-like elevations 22, and a small rectangularly-shaped depression 23, arranged between the V-shaped depression 21 and the rib

15 and bounded at all four of its sides by beveled faces 24.

What I claim is—

The design for a roofing tile herein shown and described.

In testimony that I claim the foregoing as my own I have hereto affixed my signature ...
the presence of two witnesses.

JOHN M. McCABE.
